SEPARABLE FASTENER STRINGER

Filed March 12, 1946.

UNITED STATES PATENT OFFICE

2,479,696

SEPARABLE FASTENER STRINGER

Louis H. Morin, Bronx, N. Y.

Application March 12, 1946, Serial No. 653,741

5 Claims. (Cl. 24—205)

1

This invention relates to separable fasteners of the kind in which the fastener elements or scoops are die cast directly on their tapes.

In accordance with modern methods of manufacturing and marketing such fasteners, the scoops are so dimensioned and spaced on their tapes as to provide a fixed number of scoops per unit length of stringer, conveniently, so many per inch. Accordingly, the pitch of the scoops (meaning the distance from, say, the top of one scoop to the top of the adjacent scoop of the same stringer) is carefully predetermined. Multiple cavity dies are preferably used for casting the scoops on the tapes, so that a number of scoops can be cast at one time; and, of course, the several cavities of each die half are spaced in conformity with the required pitch.

The present invention relates to a scoop-structure whereby, without affecting the pitch, a single set of dies can be utilized so to modify the scoop structure as to provide more or less play, as may be required, between the neighboring scoops of coupled stringers. The invention also results in a novel stringer assembly.

In general, the invention contemplates the use of off-set dies to produce scoops of a form in which the portions or halves of each scoop on each side of the plane of the tape are off-set with respect to each other, longitudinally of the tape. A stringer so formed is then coupled with another identical stringer. That is to say, it is not proposed to use so called "right" and "left" scoops for the respective stringers but scoops which are all of one form (actually, as produced by the same dies). As the result of the necessary reversal of position of one such stringer to point its scoops toward the scoops of the companion stringer with which it is to be coupled, the offsets, instead of meshing with one another in overlapped relation, necessarily ride on top of each other and thereby serve to take up play between the scoops.

The novel features of the invention will be best understood from the following description when taken together with the accompanying drawing, in which certain embodiments of the invention are disclosed and in which the separate parts are designated by suitable reference characters in each of the views, and in which:

Fig. 1 is a perspective view of a scoop made according to my invention, showing the same attached to the beaded edge of a mounting tape.

Fig. 2 is a longitudinal section through a few coupled scoops of a pair of stringers illustrating the arrangement of scoop halves on each stringer in the manner of compensating for play.

Fig. 3 is a view similar to Fig. 2, showing the normal procedure of forming the scoops of a stringer.

2

Fig. 4 is a view similar to Fig. 2, showing a modified form of scoop; and

Fig. 5 is a diagrammatic view showing a pair of dies and illustrating the method of casting scoops of a stringer by changing relative positions of the dies one with respect to the other.

In the formation of separable fastener stringers, difficulty has been experienced in providing coupling engagement between the scoops of a pair of stringers in a manner to prevent longitudinal play in the stringers, which in some instances may be undesirable.

It is the purpose of my invention to provide a novel and simple method of overcoming these objectionable features in the production of die cast scoops, by mounting a pair of dies in such manner as to adjust the relative positions of the dies one with respect to the other so as to form scoop halves offset one with respect to the other a distance sufficient to take-up the longitudinal play.

My invention further deals with the construction of scoops of V-shaped cross sectional form wherein coupling engagement between scoops of opposed stringers is accomplished by virtue of the V-shaped cross sectional contour thereof in retaining the scoops against transverse separation, and further wherein the coupling portions of the scoops have outer enlarged heads and inner neck portions retaining the scoops against pull apart separation.

In illustrating one adaptation of my invention, I have shown in Fig. 1 of the drawing a single scoop 10 mounted upon the beaded edge 11 of a stringer 12. The scoop 10 comprises a die cast body cast directly upon the beaded edge 11, the scoop body comprising two halves 13 and 14, integrally united at the adjacent surfaces of said halves. Each halve has a mounting end portion 15—15' disposed upon the bead 11 and the tape 12 adjacent the bead. Outwardly of the bead 11, each scoop has a projecting coupling end portion, comprising a head 16—16' of substantially hexagon cross sectional contour, and inwardly of the head is a neck portion 17—17'. The heads and necks of the scoop halves form male and female coupling portions of the scoops to retain coupled scoops against pull apart separation, it being understood that the head of one scoop fits the neck portion of adjacent scoops of an opposed stringer, as is well known in this art.

The specific structure of the head, aside from the general descriptions, given above, will not be dealt with, as these structures form no particular part of the present invention, and may be varied. It might be mentioned, however, that the walls of the heads 16—16' converge outwardly to a slight extent, as will appear from a consideration of the section in Fig. 2 of the drawing. In this figure, all background illustrations of the respec-

tive scoops is omitted for sake of clarity in illustrating the present invention. The section shown is through the heads of the scoops of one stringer and through the necks of the scoops of the opposed stringer. For illustrative purposes, the head portions of the scoops shown will designate scoops 10 of one stringer, whereas 10' will represent the scoops of an opposed stringer.

The scoop halves 13 and 14 are offset one with respect to the other, for example, the scoop halve 13 is offset upwardly to form a raised shoulder portion 18 at the intersection of the scoop halves and facing in the direction of the scoop halve 14. This also forms a downwardly offset shoulder portion 19 on the scoop halve 14, which faces in the direction of the scoop halve 13. In Fig. 2 of the drawing and to distinguish scoops of one stringer from those of a companion stringer, like structures in the common scoops 10—10' will be designated as follows.

Scoops 10' have scoop halves 13a and 14a, similar to the halves 13 and 14, and the shoulder portions 18a and 19a are similar to the shoulder portions 18 and 19, whereas 17a and 17b represent the neck portions of the scoops, similar to the neck portions 17 and 17'.

In coupling scoops of opposed stringers, the arrangement is reversed, as will clearly appear in Fig. 2 of the drawing. In other words, the halves 13 of the scoops 10 are at the left in Fig. 2, and the halves 13a on the scoops 10' to the right. It will be understood that the present illustration in Fig. 2 is exaggerated for sake of clarity, as the degree of offset between the scoop halves to take up clearance between coupled scoops will vary and may, in some instances, be very slight. The reverse arrangement of the scoop halves brings the shoulder portions 18a of the scoops 10' in alignment with the shoulder portions 19 of the scoops 10, and the shoulder portions 19a of the scoops 10' in alignment with the shoulder portions 18 of the scoop 10. This construction disposes the raised portions of the scoop halves in alignment in control of the play or clearance between coupled scoops of a pair of stringers.

In Fig. 3 of the drawing, I have shown at 20, scoops similar to the scoops 10, and at 20', a scoop similar to the scoop 10', of what is more or less conventional construction and arrangement, and in an exaggerated manner, I have shown at 21 clearances between adjacent coupled scoops, that is to say between the heads of the scoops 20 and the necks of the scoops 20'. To take up these clearances, the scoop halves are cast in the offset relationship shown in Fig. 2, producing a result substantially similar to the diagrammatic illustration of Fig. 2.

In Fig. 5 of the drawing I have shown at 22—22' a pair of dies for forming the scoops on a stringer. For example, scoops similar to the scoops 10. These dies have scoop forming cavities 23—23', which if maintained in common alignment one with respect to the other, would form scoops similar to the scoops 20 of Fig. 3. However, by mounting the dies in a manner to shift one or both dies to offset the cavities 23—23', the offset scoop halves 13 and 14 can be formed, in the manner illustrated in Fig. 5. One die may be retained stationary and the other die adjusted upwardly or downwardly to form the desired offset in the resulting scoop structure. The degree of shifting of the dies one with respect to the other will govern the take-up of clearance between the coupled scoops. It will appear from a consideration of Fig. 5 of the draw-

ing that the offsetting of the dies does not interfere in any way with the formation of scoops of what I term the coreless type, thus facilitating the formation of several scoops at a time on the beaded edge of the stringer. The entire wall structure of each scoop halve is such as to free the scoops from the dies in the separation thereof, particularly in accordance with the teachings in my prior application Ser. No. 546,180, filed July 22, 1944, now Patent No. 2,426,408.

In Fig. 4 of the drawing I have shown a sectional view similar to the showing in Fig. 2, to illustrate a slightly different form of scoop. In this construction, the scoops 24 would be similar to the scoops 10 and the scoops 24' similar to the scoops 10', the primary difference being that outer end portions of the scoop halves 25 and 26 have bevelled corner portions as at 27 and 28. This construction saves some material in the formation of the scoops, and further facilitates bending of the scoops in removing the corner extremities, as appearing in Fig. 2 of the drawing. Aside from these bevelled corner portions, the scoop structure of Fig. 4 is identical with that of Fig. 2 of the drawing. Therefore, no further description will be made. In the showing of the scoops 24' of the opposed stringer, reference characters 26a and 25a are employed to identify the scoop halves and 27a and 28a to disclose the corner portions, similar to the corner portions 27 and 28.

Considering Fig. 5 of the drawing, 29 and 30 represent adjacent surfaces of the dies 22—22', which define what is commonly referred to as the parting line of the dies. This parting line forms the line of subdivision of the scoop halves one from the other, and produces the shoulder portions, as for example, at 18 and 19.

In forming scoops on a stringer, it is a common practice to cast the scoop in what is referred to as inch increments. In order to provide a control and gage of stringer lengths, quite often a plurality of scoops of a size are simultaneously cast on the tape and this group of scoops would define the inch increment. It will be apparent that the formation of scoops in accordance with the method herein defined will in no way effect or alter this standard method of procedure in that the spacing of the scoops on each stringer is the same as the standard spacing employed. The offsetting of the scoop halves is simply to take up the play which may prevail between scoops of coupled stringers.

Having fully described my invention, what I claim as new and desire to secure by Letters Patent is:

1. A slide fastener assembly comprising a stringer tape having spaced fastener elements 60 coupled with scoops of a companion stringer tape, each scoop of each stringer being divided in the plane of the tapes into halves offset with respect to each other longitudinally of the tapes, the scoops of both stringers being identical, and the offset portions of adjacent, coupled scoops being superimposed on one another alternately on opposite sides of the plane of the tapes.

2. A pair of slide fastener stringers having reduced play between adjacent coupled scoops 70 thereof comprising: identical interengaging scoops on each stringer, each scoop comprising a pair of halves offset depthwise with respect to the scoop and throughout the length thereof to form offset portions on opposite sides of the scoop, the offset portions of the scoops of one

stringer being engaged with the offset portions of scoops of the other stringer.

3. A pair of slide fastener stringers having reduced play between adjacent coupled scoops thereof comprising: identical interengaging scoops on each stringer, each scoop comprising a pair of halves offset depthwise with respect to the scoop and throughout the length thereof to form upper and lower offset portions on opposite sides of the scoop, the upper offset portions of the scoops of one stringer being engaged with the lower offset portions of the scoops of the other stringer.

4. A pair of slide fastener stringers having reduced play between adjacent coupled scoops thereof comprising: identical interengaging scoops on each stringer, each scoop having on opposite sides thereof an outwardly extending shoulder along the entire length of the scoop, the shoulders of the scoops of one stringer being engaged with the shoulders of the scoops of the other stringer.

5. A pair of slide fastener stringers having

reduced play between adjacent coupled scoops thereof comprising: identical interengaging scoops on each stringer, each scoop having on upper and lower sides thereof an outwardly extending shoulder along the entire length of the scoop, the upper shoulders of the scoops of one stringer being engaged with the lower shoulders of the scoops of the other stringer.
